Attnys.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

1,387,107.

Specification of Letters Patent.

Patented Aug. 9, 1921.

Application filed January 16, 1920. Serial No. 351,773.

To all whom it may concern:

Be it known that I, FRED S. CARR, a citizen of the United States, and a resident of Newton, in the county of Middlesex and 5 State of Massachusetts, have invented an Improvement in Separable Fasteners, of which the following description, in connection with the accompanying drawings, is a specification, like characters on the drawings representing like parts.

This invention pertains to improvements in separable fasteners, and more particularly to separable fasteners of the three-side lock type adapted to be separated by 15 relative tipping movement of stud and socket in a predetermined manner only.

More particularly this invention pertains to improvements in the invention shown in the applications of Lars Andrew Larssen, 20 filed herewith.

It is among the objects of the present invention to provide a modification of the invention shown in the applications above referred to in which stud and socket cannot 25 be separated by an axial strain.

In the drawings, wherein I have shown a preferred embodiment of one form of my invention:—

Figure 1 is a front elevation of a portion 30 of a piece of fabric having a socket secured thereto and a stud entered in the socket;

Fig. 2 is a section on the line 2—2 of Fig. 1;

Fig. 3 is a rear elevation of the socket;

Fig. 4 is a rear elevation of the preferred 35 form of back plate shown in Fig. 2;

Fig. 5 is an end elevation of the back plate shown in Fig. 4; and

Fig. 6 is an end elevation of the preferred 40 form of stud shown in the other figures.

Referring to the drawings and to the preferred form of my invention selected for illustrative purposes, I have provided a stud of the general character shown and 45 claimed in the applications above referred to, but having a recessed portion herein shown as a second neck or groove 7, the stud being provided with a head 8 and what for the purpose of convenience I may term a primary neck 9, and preferably being slotted in the general manner shown in the copending applications above referred to.

Coöoperating with the preferred form of stud hereinbefore described, I provide a 50 socket which preferably takes the form best

shown in Fig. 2, including a plate 10 having an aperture therein through which the head 8 of the stud may pass when compressed so that the periphery of the aperture may engage the primary neck 9 of the 60 stud. That portion of the plate 10 having the aperture therein may be offset rearwardly, as best shown in Fig. 2. Coöperating with that portion of the socket engaging the primary neck 9 of the stud, I preferably provide a second part adapted to engage the recess or secondary neck 7 of the stud. This secondary part may conveniently take the form of a bead or flange 11, which may conveniently extend approximately one- 65 half the distance around the stud, and which may conveniently be formed by turning inwardly the curb or strain-receiving part 12 of the socket, this curb preferably being died rearwardly from a plate 13. The plate 70 10 and the plate 13 may conveniently be secured together by prongs 14 projecting rearwardly from the plate 10 and clenched over the plate 13.

While I have shown and described a preferred form of one embodiment of my invention, it will be understood that changes involving omission, alteration, substitution and reversal of parts, and even changes in the mode of operation, may be made without departing from the scope of my invention, which is best defined in the following 80 claims.

Claims:

1. A stud comprising, in combination, a 90 head, a primary neck and a secondary recess, said stud being resilient, and providing a greater degree of resiliency adjacent the primary neck than adjacent said recess.

2. A stud comprising, in combination, a 95 head, a primary neck, a secondary neck and a base portion, said stud split axially and said secondary neck being located more closely to said base than said primary neck.

3. A separable fastener comprising, in 100 combination, a resilient stud, circular in cross-section; a coöoperating socket for engagement with said stud; said stud and socket inseparable by direct axial relative movement and separable by relative tipping 105 movement.

4. A separable fastener comprising, in combination, a resilient stud, circular in cross-section, a coöoperating socket for engagement with said stud; said stud and 110

- socket inseparable by direct axial relative movement and separable by relative tipping movement in a predetermined direction only.
5. A separable fastener comprising, in combination, a stud having a head and a neck and a recessed portion; a coöperating socket providing an aperture having marginal portions for engagement with said neck and a coöperating part for engagement in said recessed portion, said stud and socket separable by relative tipping movement in one direction only.
10. A separable fastener comprising, in

combination, a stud having a head, a neck 15 and a recessed portion, said stud split longitudinally to provide resiliency; and a socket providing a jaw plate having an aperture therein with neck-engaging marginal portions, and a second piece carrying a recess-engaging part, said plate and said second piece located on opposite sides of the carrying fabric and secured together by clenched prongs.

In testimony whereof, I have signed my 25 name to this specification.

FRED S. CARR.
